BRASSIÈRE AND BREAST PAD

William Rosenthal, New York, N. Y., assignor to
 Maiden Form Brassiere Company, Inc., New
 York, N. Y., a corporation of New York

Application September 17, 1935, Serial No. 40,890

5 Claims. (Cl. 2—42)

This invention relates broadly to a new brassière construction.

One of the objects of this invention is the creation of a brassière which is adapted to support the bust in natural position.

Another object of this invention is the creation of a brassière embodying means whereby a wearer naturally having a small and meager bust by wearing same may be made to appear to have an ample and satisfactory configuration of bust line.

Another object of this invention is the creation of a brassière embodying means contained in the breast receiving pockets for also receiving and holding bust forms or pads which are pre-shaped and formed so as to simulate the shape and form of a partial breast and which are adapted to complete the filling out of said breast receiving pockets.

Another object of this invention is the creation of a brassière of such construction and embodying such appurtenances that, when worn by a substantially flat chested individual, will lend to the wearer an unnoticeable external appearance of naturally having a normal bust configuration.

A still further object of this invention is the creation of a novel breast form or pad which is firm, yet relatively soft, and which may be readily, firmly and securely supported by and carried in a breast receiving brassière pocket to unnoticeably supplement the wearer's breasts and yield an external appearance of ample and proper bust contour and which form or pad is readily separable from the breast receiving brassière pocket for purposes of cleaning; repairing, mending and the like.

A still further object of this invention is the creation of a breast form or pad having a moisture-proof outer surface so constructed that said form or pad may be readily washed or dampened by perspiration without wetting or dampening the material contained there within and accordingly, surface dried and used without the loss of time and shape which would be attendant upon the drying out of moisture from the interior of the body thereof.

A still further object of the invention is the creation of a brassière having breast receiving pockets therein constructed of irregular shaped pieces to provide a comfortable and conformable arrangement, without Shirring, which might cause irritation to the wearer's skin.

Various other objects and advantages of the invention than those hereinabove mentioned will appear more fully hereinafter. It is to be understood, that the specific forms shown are

merely illustrative and hence the detailed description thereof is not to be taken as limiting the invention itself.

This invention resides substantially in the parts as well as the combination, construction, arrangement and relative location of parts, all as will appear more fully hereinafter.

Referring to the drawing, in which the same reference numerals are used throughout the several views to indicate the same or similar parts, it will be found that:

Fig. 1 represents a front elevational view of a brassière employing the novel principles of my construction;

Fig. 2 represents a rear elevational view thereof;

Fig. 3 represents a sectional view, taken along the section line 3—3 in Fig. 1, looking in the direction of the arrows;

Fig. 4 is a detail plan view of a partly stitched internal breast pad element, and

Fig. 5 is a rear perspective view of my novel brassière construction with breast pads in place, all shown in wearing position.

It is well known that heretofore women naturally having small and meager breasts or having an abnormal inequality between their breasts in respect to size or even lacking a breast or breasts because of a surgical operation or the like, have been compelled to either suffer the natural embarrassment of having a deficient and unsatisfactory bust configuration or else attempt to disguise such condition by the employment of garments adapted to hide their true breast configuration.

Such individuals, of necessity, have often resorted to many unsatisfactory measures such as either the employment of loose and ill-fitting blouses, waists and dresses adapted to completely hide by flowing lines their breast configuration or else encircling their body with an overheating multiplicity of garments in order to obtain by a plurality of thicknesses of fabric an artificial external appearance of satisfactory breast configuration. Such individuals, however, have not, of course, worn brassières but rather have been deprived of the advantages attaching to the proper breast support derivable therefrom. Indeed, no comfortable, secure and satisfactory brassière previous hereto has been created which could be worn by such an individual.

Moreover, as is further well known, the trend in present day style is towards accentuation of the natural breast and body lines so as to emphasize the inherent beauty in the natural curves

of the well developed human form. Thus a woman having small breasts finds herself outmoded, unable often to wear and make use of current styles particularly of outer wearing apparel and accordingly unable to keep in step with current fashion.

Such devices as have been created heretofore in attempts to ameliorate this situation and supplement the form and figure of the wearer have proven clumsy, crude, insecure against slipping, often extremely uncomfortable, wholly impractical, as well as expensive and generally unsatisfactory and to say the least, ultimately, by far more embarrassing to the wearer than being entirely without any such artificial devices.

It is the purpose of this invention, therefore, to provide a novel type of brassière of novel pocket construction which contains means in either or both breasts receiving pockets for detachably yet securely and firmly holding against slipping a novel pre-shaped and formed breast pad to supplement the wearer's bust configuration to the desired extent and which pad once mounted in the breast receiving pocket is secure against slipping about or out of the pocket and requires but little further attention.

As will be apparent hereafter, my novel brassière with breast pads once in place may be worn as a composite unit, without the pads being in any way externally noticeable. An almost life-like shape of substantially natural resilient firm softness is produced thereby and externally an observer is unable to determine whether the breast line of the wearer is actual or artificial. The novel breast pads employed, as will be disclosed, are covered with soft moisture-proof material and the brassière is so constructed that its inner surface is soft throughout and without raised seams or of other irritation producing construction.

Referring now to the drawing for a specific example of my novel construction it will be noted particularly from Figs. 1 and 2 that I have shown a brassière having two breast receiving pockets 1 and 2, secured together along a line of seam 3, and having back bands 4 and 5 secured to the free ends thereof. Attached to the free end of back band 5 is an elastic section 6 which acts as a back section and which in turn has at the free end thereof 7 a plurality of fasteners 8 adapted to cooperative engagement with hooks 9 carried on the free end of back band 4 so as to secure the brassière about the body of the wearer.

Behind fasteners 8 is a small piece of fabric 10 adapted to over-lap the fasteners and hooks, 8 and 9, when engaged, to separate same from the body of the wearer and keep same from contact with the skin of the wearer thus eliminating all possible consequent irritation that might be caused thereby.

Attached to the upper edges of each of the pockets 1 and 2 are shoulder straps 11 and 12 which at their free ends are secured to back bands 4 and 5 by elastic members 13 and 14. It will be noted that each of the breast receiving pockets 1 and 2 are preshaped and given pocket and cup-like form by joining together an upper piece of fabric 15 having a shallow substantially V-like shape and a lower piece of fabric 16, having a co-operative and correspondingly shallow substantially V-like cut along a line of stitch 17 which may be termed a bent line of stitch because of the position thereof when the pockets are in wearing position.

Turning next to the inside of the pockets, it will be noted particularly from Figs. 2 and 5 that an upstanding piece of fabric 18 having a substantially semi-circular lower edge is secured in each breast receiving pocket by a semi-circular line of stitching 19 but at a sufficient distance from the apex of the pocket to form with the brassière pocket fabric a snug breast pad receiving cavity or receptacle, the distance from the apex depending upon the height of the breast receiving pad to be received and held. The pieces of fabric 18 as particularly shown in Figs. 2 and 5 are adapted to upstand from the fabric of the breast pockets and are formed with sloping or tapering edges 20 adjacent their straight upper edges 21 so that the breast pads may be held by dovetailing in position as hereinafter described. It will also be noted that the line of stitching 19 is continued along edges 20 so that they also are stitched to the fabric of the breast receiving pockets thereby leaving only the upper edges 21 free.

Turning next to Fig. 3 it will be noted that each breast pad 22 is generally more or less conical in shape and may be shaped to give any desired natural configuration. I prefer to make same of an outer moisture-proof encasing sheet of soft rubberized material or the like 23 within which are disposed a plurality of layers of cotton or the like 24 and a plurality of layers of felt 25 or the like 26. As shown in Fig. 3 there are three layers of cotton or the like 24, the largest being adjacent the bottom of the moisture-proof encasing 23, the next largest being against the first mentioned cotton layer and the last being relatively small and being adjacent the second mentioned cotton layer on one side and adjacent the first and smallest layer of felt or the like 25 on its remaining side. It will be further noted that each of the three layers of cotton or the like 24 are more or less relatively flat compared to the felt elements 25 which are cup-like in form. Turning to Fig. 4 it will be noted a typical felt element 25 is there shown. Each felt element is composed of two members 26 being provided with lines of substantially V-cut 27 at both sides. As shown, the lines of cut 27 on the left side of element 25 in Fig. 4 have been brought together by stitching 28 while the lines of cut 27 appearing on the right side of element 25 in Fig. 4 have not yet been sewed together. By bringing the lines of cut 27 together the felt elements 25 are caused to assume a cup-like formation as may be distinctly observed in the sectional view shown in Fig. 3. By causing the cup-like elements 25 to successively increase in size from the center of the pad and by fitting one cup like element 25 within the next larger cup-like element and thereby nesting said elements, a conical pad-like element is built up. It is to be understood, of course, that the largest cup-like element 25 will be next adjacent to and within the outer moisture-proof encasing sheet of rubberized material or the like 23.

It will be further understood that the outer felt cup-like element 25 may be even secured to the encasing moisture-proof element 23 by a line of stitching 29. If the encasing sheet element 23 is made of stitched together pieces of rubberized material then the line of stitching 29 used to secure the pieces together may and is used as well to hold the next adjacent and largest felt element 25 to the casing 23. Appropriate stitching at 30 runs completely around the conical pad at the 75

base thereof so as to secure the edges together and permit of binding.

It will also be noted from Fig. 3 that by appropriate stitching and folding the upper straight edge 21 of the elements 18 may be appropriately bound, stitched and finished as shown at 31 and that likewise the upper and lower edges 32 and 33 of the brassière pocket are appropriately stitched, bound and finished so as to give a smooth and even finish to the complete garment.

It will be understood, of course, that the selection of materials to go within the breast pad depends upon the degree of softness and resiliency that it is desired be imparted thereto. It will also be understood, that I have found that a very desirable pad well adapted to attain the purposes of my invention will be produced by following the constructions which I have just outlined. However, I desire it to be understood, that it is within the spirit of my invention that other pads embodying different materials or a different number of layers or even possibly of somewhat different shape or construction might likewise be employed with desirable results and I accordingly, therefore, do not desire to be limited to any specific material, shape or number of layers in the construction of the breast pad.

It will be further noted from the foregoing that the breast pad that I have shown while substantially generally conical in form, has a more or less oval-like shaped base as will be readily apparent from Figs. 1, 2 and 5 which base has more or less sharply defined ends or points 34 adapted to fit within the point-like recesses formed by the tapering edges 20 of the circular elements 18 with the fabric of pockets 1 and 2 so as to dovetail the pad against slipping out of the breast-pad-receiving receptacle formed by the fabric of the breast receiving pockets and the element 18.

Having thus described my novel construction, I will now briefly describe the manner in which the same is used:

In this connection it will be understood that a woman having small breasts will naturally select and purchase a proper sized brassière and pads in conformance with her needs. Having secured the garment, the woman may, to care for abnormalities, desire to remove but one breast pad. In order to do this she need only grasp the upper edge of the pad and squeeze same slightly between her thumb and forefinger so as to compress same sufficiently to avoid the dovetailing effect caused by the shape of the edge of the base of the pad and edges 20. When this has been done she may readily slip one of the breast pads out of the breast-pad-receiving receptacle and may then use the remaining breast receiving pocket to receive a large and normal single breast. This is true inasmuch as the element 18 would not seriously interfere with the employment of the breast receiving pocket to receive a large and normal breast, it being clear that said element in the absence of a breast receiving pad, may be readily forced down against the fabric 16 of pockets 1 or 2.

While, of course, the brassière I have described may be used with but a single breast pad by an individual having such needs, I intend the same to be primarily used with both pads by individuals having two small breasts, the proportions of which it is desired be amplified.

It is to be understood further that in such case the wearer's small breasts will fit within the breast receiving pockets directly behind the element 18 and since both the element 18 and the pad 22 are

conformable and soft, an appropriate concavity or depression in the bottom of pad 22 such as is shown by the depression or concavity at 35 in Fig. 3 will result, so that the outline of the actual breast will be closely met by the bottom of the pad without external noticeable effect. The breast pads I have disclosed are more or less resilient in construction, and will return to and retain a substantially flat bottom when the rotundity of the wearer's breast is removed from contact with the substantially flat bottom thereof. These pads are also readily removable from the pockets not only for the possible uses hereinbefore mentioned but also so that a wearer desiring to clean the garment may readily remove the pads, wash the brassière in the customary fashion, and, as will be readily understood, cleanse the pads by a mere washing over, without fear of dampening the absorbent materials contained within the moisture-proof enclosing casing.

It will be obvious from the foregoing that the brassière construction I have disclosed incorporates many features which are possible of general adaptation in brassières other than those containing breast pads. For instance, the pocket construction disclosed may obviously be conveniently and valuably employed in connection with all types of brassières.

Moreover, the construction herein disclosed might be satisfactorily and successfully employed in cases where surgical treatment of the breast has resulted in the complete removable of the whole of one or more breasts in which cases, the shape and size of the breast pad employed would have to be varied to meet the individual case.

I am, of course, aware that many changes in the details of construction and relative arrangement of parts will readily suggest themselves to those skilled in the art and I do not, therefore, desire to be limited to the exact details herein set forth by way of illustration, but rather to the spirit and scope of my invention as I define it in the appended claims.

What I seek to secure by and claim for United States Letters Patent is:

1. In a garment of the type described the combination of two fabric breast pockets secured together by stitching, each of said pockets being formed of an upper and a lower section of fabric secured together by a bent line of seam, a portion of fabric having a substantially semi-circular lower edge, a straight upper edge and straight side edges inwardly sloping from said lower edge to said upper edge to form point-like recesses, said portion of fabric being secured at and along said sloping edges and said lower edge to the lower section of fabric of the breast pocket by corresponding lines of stitching so as to form a breast pad receiving cavity with the fabric of each breast pocket and a breast pad adapted to fit within such cavity and having a bottom edge so formed that said pad is held against displacement by a dovetailing action between the sloping side edges of the fabric portion and the bottom edge of the breast pad.

2. The construction recited in claim 1 characterized in that the breast pad is of substantially breast-like form and is provided with an oval-like shaped base having ends adapted to fit within point-like recesses formed by the sloping edges of the portion of fabric which is secured within each breast pocket and the fabric of such pockets.

3. The construction recited in claim 1 characterized in that each breast pad is entirely en-

closed in an outer moisture proof casing and has a soft conformable base resting against the portion of fabric secured in the pocket in which the pad is disposed said base and contiguous fabric being adapted to closely conform to the outline of the wearer's breast therebehind.

4. In a garment of the type described the combination of a fabric breast receiving pocket, a substantially vertical fabric wall having a curved lower edge, a substantially straight upper edge and straight side edges inwardly sloping from said lower edge to said upper edge, said fabric wall being secured at and along said sloping side edges and said curved lower edge to the lower portion of the fabric of the breast receiving pocket by corresponding lines of stitching so as to form a breast pad receiving cavity having point like recesses and a breast pad adapted to fit within such cavity, said pad having the edge of its bottom surface so formed that said pad is held against displacement in said cavity and recesses by a dovetailing effect between the aforementioned sloping side edges of the fabric wall and the fabric of the breast pocket with the edge of the breast pad bottom surface.

5. In a garment of the type described, a breast receiving pocket, a pad receiving pocket formed

in the apex of the breast receiving pocket, said pad receiving pocket having point-like recesses below its top and a restricted opening at its top, said opening having a transverse width less than the transverse width of the portion of the pad pocket immediately below such opening, and a unitary, pliable, and compressible breast pad of a shape substantially like the forward portion of a female breast, said pad having a base formed with point-like ends adapted to insertion in and disposition within the aforementioned point-like recesses in the pad receiving pocket, and which ends, when not pressed together for purposes of inserting the pad into the pad receiving pocket are separated by a distance greater than the transverse width of the aforementioned restricted opening; said pad being adapted upon disposition in the pad pocket to fill out the apex of the breast receiving pocket; all with the aforementioned differences in widths resulting in the pad, whence once within the pad receiving pocket, being held against displacement by a dove-tailing effect between the respective point-like ends of the base of said pad and the respective point-like recesses of the pad receiving pocket.

25

WILLIAM ROSENTHAL.
